UNITED STATES PATENT OFFICE.

FRANK B. TWINING, OF TROY, NEW YORK, ASSIGNOR TO GEO. P. IDE & COMPANY, INC.,
OF TROY, NEW YORK, A CORPORATION OF NEW YORK.

MULTIPLY INTERWOVEN FABRIC FOR COLLARS AND CUFFS.

Application filed August 15, 1921. Serial No. 492,500.

To all whom it may concern:

Be it known that I, FRANK B. TWINING, a citizen of the United States, residing at Troy, in the county of Rensselaer and State 5 of New York, have invented certain new and useful Improvements in Multiply Interwoven Fabrics for Collars and Cuffs, of which the following is a specification.

For many years collars have been made of 10 a plurality of separate plies and fillers, each ply being cut according to the desired pattern, and the plies then associated and stitched together at their edges, so that the various plies and fillers are connected together 15 only at their edges along the lines of stitching. The neck band and the fold over top portion of the so called "turn down" collar are then connected together by means of rows of stitching.

20 This method of manufacturing a collar necessitates many handlings of the various plies, consequently there are many manufacturing operations incident to collars as heretofore made, each operation adding to 25 the cost of manufacture.

One of the objects of my invention is to reduce, very materially, the number of operations necessary to produce a collar.

A further object of my invention is to produce 30 a soft fold over collar from a single piece of multiply interwoven fabric, of appropriate thickness or stiffness.

A further object of my invention is to produce 35 a soft fold over collar from a single thickness of multiply interwoven material of appropriate stiffness or thickness, having a narrow thickened cross sectional area extending in the direction of the warp threads.

My invention consists further of a multi- 40 ply interwoven fabric for collars and cuffs, having woven therein additional warp threads in a comparatively narrow zone.

My invention consists further in a multiply interwoven fabric for collars and cuffs 45 consisting of two panels connected integrally by a comparatively narrow portion having an increased number of warp threads.

For the purposes of illustrating my in-

vention I have shown the fabric in the drawing as being made in the shape of an elongated strip just sufficiently wide to enable one to cut a collar lengthwise therefrom, but, of course, it will be understood that the fabric may be woven any suitable width from which collars may be cut economically.

50 In the drawings.

Figure 1 is a top plan view of the fabric embodying my invention.

Figure 2 is a vertical section on the line 2-2 of Figure 1, on a larger scale.

The multiply interwoven fabric is woven according to the regular practice now in vogue in weaving multiply interwoven fabrics, the only change in the weaving of the fabric being that at a predetermined point 65 the operator introduces a greater number of warp threads for a predetermined width in the formation of the fabric, whereby the cross sectional area of the fabric is increased in thickness in the direction of the warp 70 threads in a comparatively narrow zone so that after the collar is cut from my improved fabric with the panel 1 as the neck band and the panel 2 as the fold over top portion, the increased thickened zone 3 functions 75 as a guide line for the folding of the collar.

The edges of the collar, after being cut from the fabric, may be finished in any manner found most desirable by the manufacturer.

I do not claim herein the collar made from the fabric as that constitutes the subject matter of another application for patent filed by me August 15, 1922, Serial No. 85 492,499.

What I claim is:

A multiply interwoven fabric for collars comprising panels interwoven in one piece, one panel forming the neck portion, another 90 the turn down portion of the collar, and a comparatively narrow zone having an increased number of warp threads, the edge of said zone defining the fold line of the collar.

In testimony whereof I affix my signature. 95
FRANK B. TWINING.
